UNITED STATES PATENT OFFICE.

HALCOLM ELLIS, OF EAST ORANGE, NEW JERSEY.

MULTIPLE-ACCUMULATOR ADDING AND LISTING MACHINE.

1,197,278.

Specification of Letters Patent.

Patented Sept. 5, 1916.

Application filed November 24, 1915. Serial No. 63,273.

To all whom it may concern:

Be it known that I, HALCOLM ELLIS, a citizen of the United States, residing at East Orange, county of Essex, and State of New Jersey, have invented certain new and useful Improvements in Multiple-Accumulator Adding and Listing Machines, of which the following is a specification.

This invention relates to multiple accumulator adding and listing machines.

The present invention embodies improvements on the controlling means for the adding and listing mechanism of the machine of my application, Serial No. 470,108, filed December 30, 1908, and is particularly applicable thereto, although these improvements may be applied to any adding machine or adding and listing machine employing two or more accumulators adapted to be independently or conjointly engaged with key-controlled actuators.

The machine of my aforesaid application may be conditioned for the performance of addition in either or both of the accumulators by the use of certain controlling keys which I denominate "operating" keys or by setting the traveling platen carrying carriage in tabulating position, or items may be listed or printed without being added into either or both of the accumulators by the use of a non-add key.

When it is desired to simultaneously or conjointly add the items into both accumulators by using the operating keys and a total is thereafter desired to be taken from either accumulator, unless the remaining accumulator is first disconnected from the racks or actuators, the act of taking a total results in adding that total into the other accumulator and gives a false condition in the second accumulator.

In the machine of my aforesaid application, the control of the accumulators by the disposition of the traveling platen carrying carriage in tabulating position, automatically conditions one or both of the accumulators for addition according to the nature of the stop employed on the carriage. If the stop is provided with a point or projection in one location, it will condition the mechanism so that but one of the accumulators is arranged for addition; if the point or stop is otherwise disposed, it will be adapted to arrange the other accumulator for addition; if two stops are used, both con-

trolling mechanisms will be actuated when the carriage assumes tabulating position and both accumulators will then be conditioned for the reception of items to be added. If, then, with both accumulators conditioned for addition by the tabulated position of the carriage, a total is taken from one accumulator by the use of the proper operating total key for that accumulator, the act of taking such total will result in the transfer of the amount of the total into the second accumulator, resulting in a fictitious addition in the second accumulator. However, in that machine, if the carriage is moved from tabulating position before the total is taken, the fictitious result in the second accumulator will not follow when a total or sub-total key is depressed.

In the machine of my aforesaid application, if an accumulator is set or conditioned for addition, it will add, regardless of whether the actuators or racks are limited in their travel by the key-board or by another accumulator and this is the reason why if both accumulators are in engagement with the racks or actuators for purposes of addition and a total is taken from one accumulator, that total will be automatically transferred into the remaining accumulator.

In the machine of my aforesaid application, when it is desired to merely list or print items without adding them, either when the carriage is in tabulating position or when one or both accumulators are set for addition by the operating keys, it is necessary to hold the non-add key depressed by the finger if more than one item is to be listed without being added.

One of the objects of my invention is to provide in a multiple accumulator adding machine wherein the accumulators may be individually or conjointly caused to engage actuators for the purpose of addition, means whereby when the accumulators are conjointly engaged with the actuators for adding into all of them simultaneously, if so desired, on the taking of a total from any one of the accumulators, all other accumulators will be automatically placed in a non-add condition so that the taking of the total from the given accumulator will in no manner disturb the original setting of the remaining accumulators or give a fictitious result therein if further additions are performed on the machine. The mechanism

for the accomplishment of the object just indicated is adapted to coöperate with the total and sub-total keys so that, on the operation of any one of them, regardless of 5 which accumulator is controlled thereby, the devices which control the setting of the accumulators in adding position are blocked against operation, and hence, the total or sub-total is taken without disturbing the 10 condition of the other accumulators.

In the present invention, the independent operation of the non-add key is in no manner interfered with and such key may be depressed for the listing and printing, without 15 adding, of any item or items. Preferably, the same blocking device is utilized to coöperate with the non-add key that is controlled by the total and sub-total keys.

When the total or sub-total key is restored, 20 after taking the total or sub-total, the controlling mechanism for the accumulators is unblocked and the machine is then restored to the condition where the accumulators may receive further additions.

25 A further improvement contemplated by the present invention is the automatic conditioning of the machine to prevent addition in any accumulator, if set for addition, when the traveling platen carrying carriage 30 is in tabulating position so that items may then be set up and printed one after another without performing addition and without necessitating depression of the non-add key. To that end, I provide means adapted to 35 block the devices which control the accumulators for purposes of addition, such means being set into position to prevent addition when the carriage is in tabulating position. A stop is provided on the 40 carriage which is adapted, through appropriate intermediate means, to shift the blocking non-add device or lever just as it is shifted when the non-add key or the 45 sub-total or total keys are depressed. Consequently if the carriage is moved to non-add position when either or both of the accumulators happens to be set for addition by the adding keys, the stop on the carriage operates the blocking mechanism 50 and all of the accumulators are locked so that they cannot operate. Another stop having two points may be employed on the carriage (as in my aforesaid application) 55 so that the latches for the accumulator controllers will be released when the carriage is in adding tabulating position and, in that event, there will be no automatic blocking, by carriage control, of the accumulator controllers.

60 Means are provided for automatically unlocking the handle or the starting bar, as the case may be, by the depression of a total or sub-total key, or the non-add key, and when the carriage is in non-add tabulating position. Provision is thus made for

addition when the carriage is in one tabulating position and for printing, without addition, when in another tabulating position.

The embodiment of the invention herein- 70 after set forth and disclosed in the drawings is for the purpose of identifying the improvements with the machine of my co-pending application, Serial No. 470,108, filed December 30, 1908.

75 My improvements might be utilized on other machines and the disclosure is, therefore, to be considered as illustrative, rather than restrictive, of the scope of the invention.

80 In the accompanying drawings: Figure 1 is a vertical, longitudinal section through the mechanism for the adding and printing of numbers of the machine of my co-pending application, so much of the machine 85 being illustrated as to afford a clear idea of the application and functions of my improvements which are shown in other figures; Fig. 2, a left-hand elevation of the multiple accumulator section of the machine of my co-pending application; Fig. 3, an elevation of the left-hand side of the said machine showing my improvements applied thereto; Fig. 4, a detail elevation of the operating keys, certain of my improvements, and the parts of my aforesaid machine directly associated therewith; Fig. 5, a perspective showing those parts of my improvements, and associated mechanisms of my co-pending application, having to do 90 with automatic control of the accumulators by the carriage tabulating mechanism; Fig. 6, a perspective detail of certain of the present improvements alone; Fig. 7, a detail of the one-point tabulating stop; and 95 Fig. 8, details of the sliding setting and restoring bars.

100 *General construction.*—Referring first to Fig. 1, the numeral keys are shown at K51, K52, K53, K54, K55, K56, K57, K58, K59, representing numerals "1" to "9" inclusive. There are nine rows of keys similar to those shown. The keys are raised by springs K80 and are provided with stops K23. There are nine racks or actuators R50 having steps arranged vernier fashion in such manner that the engagement of a rack R50 with any stop K23 will permit a definite extent of sliding movement of the rack R50. For instance, if key stem K54 is depressed and the rack R50 moved to the rear until it engages, the stop K23 on stem K54, there would result a movement of four teeth of those shown at R50 past the bar R92. If, at this time, the adding wheel A50 is made to engage the rack R50, and the latter is then restored so that it assumes the position shown in Fig. 1, the adding wheel A50 will be rotated a distance of four teeth.

105 Mounted on the shaft R1 are levers R45,

of which there are as many as there are printing type sectors P54 and corresponding in number to the rows of numeral keys K51, etc. Arms or levers P53 connect the respective levers R45 to the type sectors P54 through pivots 15R and P10. The type sectors P54 are pivotally carried at P11 on arms 52P which are loosely mounted on shaft P1. Appropriate means, set forth in my co-pending application aforesaid, is combined with the parts described, whereby the type sector or sectors may be advanced, as shown in dotted lines, Fig. 1, to print any item desired to be printed or to print a total or sub-total corresponding to the number represented by the respective positions of the racks or actuators R50. Movements corresponding to those of the racks R50 are imparted to the three-armed levers R45 through the pin-and-slot connections R14.

Multiple adding section.—The mechanism of the duplex or multiple accumulator being the same as set forth in my co-pending application aforesaid, only sufficient description is given to afford a clear understanding of the relation of my improvements thereto. This mechanism is a complete unit, the left-hand end thereof appearing, as shown in Fig. 2; and with its case attached as at the left of Fig. 3. The showing of the adding mechanism at the right of Fig. 1 is partly in dotted lines for the purpose of better illustrating the movements of the frames which carry the adding wheels and the operation thereof. There are two sets of adding wheels A50, respectively adapted to engage the upper and lower teeth R50. Either set of adding wheels may be engaged with the teeth 50R at a given time, or both sets 40 jointly engaged therewith so that adding may take place in both sets of wheels simultaneously. The sets of adding wheels are mounted in swinging frames A48 pivoted at 16A and having a limited swinging movement up and down. The shafts A2 of the adding wheels A50 project beyond the sides of the frames A48 and have suitable rollers operating in the cam slots of two cams A59 and 59A, respectively, the cams being carried by shafts A1 and 1A for the purpose of bringing the adding wheels A50 into and out of engagement with the racks R50. The shafts A1 and 1A are turned by suitable cranks A67 and A68 and are held at each 55 end of the stroke by the detents A69. The carrying mechanism for the respective sets of adding wheels A50 embodies, in part, devices shown at A52, A53, A54 and A56; also pieces A49 and 49A pivoted at A16, whose operation it is unnecessary to set forth, as these parts constitute no part of my present improvements and are fully disclosed in my co-pending application aforesaid.

The machine is provided with a handle and operative connections, not shown, for

putting it through its cycle of operations in adding, listing, and taking totals and sub-totals. The power is applied to the shaft O1 on which is secured the irregular plate D50 whose movement, under different conditions which can be predetermined, controls the movement of the accumulators into and out of engagement with the racks 50R.

Operating or controlling keys.—Referring to Figs. 3 and 4, the keys which are shown at K61, K62, K63, K64, K65, K66, K67, K68, K69, are termed "operating" keys because the depression of any one of them in conjunction with the operation of the handle or power means causes the machine to perform some special function or to entirely omit that function. The key K61 is a release key for releasing any numeral key or any other operating keys which have been previously depressed; K62 is a repeat key whose function is to prevent the release of the numeral keys by the operation of the handle so that an item may be repeated; K63 is the total key for the upper set of accumulators; K64 is the sub-total key for the same set of accumulators; K65 is the adding key for the upper set of accumulators. The total key for the lower set of accumulators is shown at K66; the sub-total key for the same set of accumulators at K67; K68 is the adding key for the lower set of accumulators. K69 is the non-add key. These keys are spring raised.

Total keys and sub-total keys are made interlocking and the non-add key made interlocking with the total keys by means of danglers L50 coöperating with pins K12 on the said keys. On the depression of one of these specified keys, interlocking occurs. A lever D69 coöperates with the series of danglers and when the plate D50 is in normal position, as in Fig. 3, a pin D14 engages the lever D69. When the shaft O1 is operated, the lever D69 is released and then swings the danglers L50 to the right, causing them to engage pins K12, thus closing the passage between them and preventing any of the keys K63, K64, K66, K67, K69 from being depressed.

Means for setting accumulators.—Pivotally carried by the plate D50 at D14 are the flying levers D53 and D54, the first of which is connected to the crank A67 by the link D56 and the latter to the crank A68 by the link D57. If these levers are not arrested, the movement of the piece D50 by the turning of shaft O1 will not cause the cranks A67 or A68 to swing, and consequently, the sets of adding wheels of the two accumulators will not engage the racks of the actuators R50. The respective levers carry pivotally mounted hit or miss pieces D51 and D52 which are retracted by springs D82 against pins on the levers. The controllers for the operation of adding are the piv-

oted pieces D58 and D59, respectively controlling the upper and lower accumulators. These pieces D58 and D59 have pins D21 and D22 respectively positioned to be engaged by the hit or miss pieces D51 and D52. Pivoted latches D60 and D61 are arranged to normally engage the controller pieces D58 and D59 to hold them latched. When this condition prevails, the swinging 10 of the piece D50 results in the tails of the hit or miss pieces D51, D52 engaging the pins D21, D22 and the hit or miss pieces are then positioned so that they will not engage the pins D12, and consequently no 15 rigid connection exists between the plate D50 and the cranks A67 and A68. Neither accumulator is, therefore, shifted and no addition occurs. If, however, the latch D60, for instance, be disengaged from the piece 20 D58, the spring D81 of the piece D58 moves it and when the piece D50 swings by an operation of the handle of the machine, the tail of the hit or miss piece D51 is not interfered with and the said piece D51 then 25 engages the stop D12 and a rigid connection consequently ensues, resulting in the shifting of the link D56 and the engagement of the upper accumulator with the racks 50R. To restore the pieces D58 and D59 to latching 30 position, there are provided the parts D66, D67, the former engaging the pins D21, D22, and the latter being engaged by the pivot D14 of lever D53 when the piece D50 assumes the normal position shown in Fig. 3.

35 The latches D60, D61 are under the control of a stop on the traveling carriage when the latter is in tabulating adding position and they are also controlled by the adding keys K65 and K68 of the respective accumulators.

40 The adding key K65 is provided with a notch *n*. A lever L57 has an angular upper end adapted to engage the notch *n* when key K65 is depressed. A spring co-acting 45 with the lever holds its bent end against the key stem K65. The other end of the lever L57 has a pin L23 which engages the right-hand end of the latch D60. When the key K65 is depressed, the end of the lever L57 enters notch *n* and disengages latch D60 from controller piece D58, which will set the parts for adding in the upper accumulator. A lever 57L performs the same function as the lever L57 with respect to the 55 adding key K68 for the lower accumulator and the latch D61 for the controlling piece D59.

Releasing the latches D60, D61 in an automatic manner by the position of the carriage is effected through upright links D64 whose lower ends are connected to the latches D60, D61.

Referring to Fig. 5, an adjustable stop corresponding to stop C96, but having two 65 depending points adapted to engage the tips

w of the intermediate levers F61 connected to the links D64, may be provided at any desired point on carriage rack C91 for the purpose of automatically disengaging the latches D60, D61 from the controlling pieces 70 D58, D59 when the carriage is in tabulating adding position, as proposed in my copending application, but immediately the carriage has been spaced therefrom, the latches D60, D61 re-set themselves and consequently 75 lineal addition can only be performed by the use of the operating keys, K65 for the upper accumulator, and K68 for the lower accumulator. The stop C96 illustrated is not of the two-point form as in my copending application, but of an improved form, as in Fig. 7, for use as a non-add stop, as hereinafter set forth.

Coöperating with the total and sub-total keys K63, K64, are levers L56 and 56L, 85 which in turn, have pins L19, L18 adapted to engage cam surfaces on a piece 58L pivoted at L24. When the piece 58L is depressed by the depression of either lever K63 or K64, its coöperation with a pin L22 on a piece 60L which is pivoted at 19L, causes 90 the elevation of the extreme left-hand end of piece 60L so that it will be in position to engage the lower end of the flying lever D53 and offer an abutment thereto when the piece D50 is turned with the shaft O1. This results in locking the flying lever D53 against the stud D13 and causes movement of the link D56 and adding crank A67. Afterward, the lower end of lever D53 passes over 95 the left-hand end of lever 60L and over the upper end of a piece L62 which is pivoted at 19L. On the return movement, the lower end of lever D53 trips over the upper end of the piece L62 and the crank A67 is swung 100 back to normal position.

The total and sub-total keys K66 and K67 have levers L59 and L60 coöperating therewith in the same manner as the levers L56 and 56L coöperate with the keys K63 and 110 K64. The pins on the levers L59 and L60 coöperate with the piece 59L which in turn, coöperates with a pin on a lever 61L corresponding to lever 60L, and there is a second piece 62L which corresponds to the 115 piece L62. The parts just described are adapted to coöperate with the flying lever D54, and through it, to control the link D57 and crank A68.

A sliding bar L66 is mounted on a swinging cam L54 at its forward end and over a stud L27 near its rear end. The bar L66 has projections *p* on its upper edge arranged to engage the upper ends of the latches or levers L56 and L59, so that if 125 the piece L66 be moved to the rear, it will re-set said latches or levers and thus release the key stems controlled thereby and also the pieces 58L and 59L. On the rear end of the bar L66 is a pivoted lever L67 130

which is normally held in the position shown in Fig. 3 by a light spring L84. The rivet 15D on the rear of the plate D50 is adapted to engage the piece L67 on the 5 advance of the piece D50 without having any effect. On the return stroke of the piece D50, the rivet 15D engages the forward side of the piece L67 and swings it until the upper end thereof engages the stationary pin L29. Further movement ensuing, the lever L67 is moved, and with it, the bar L66, whereupon the projections p disengage the latches before mentioned.

A bar L65 similar to and located just 15 back of bar L66 and provided with suitable upwardly extending projections p' engages the latches 56L and L60 for the sub-total keys and is pivoted at its rear end to the upper end of a lever L68 whose lower end 20 is located in the path of travel of the inner end of pivot D14 of piece D50. When the plate D50 moves to its extreme forward position, the pin D14 engages the lower end 25 of lever L68 and causes it to move to the rear a sufficient distance to cause disengagement of the latches 56L and L60 from the key stems K64 and K67.

In the operation of taking a sub-total, the initiation of movement is the same as for 30 taking a total, but at the forward end of the movement of the plate D50, the pin D14 positively engages the lever L68, which causes retraction of the bar L65 and the release of the sub-total key which has been set. 35 The resumption of initial position of the piece 60L or 61L prevents it from engaging the lower end of flying lever D53 or D54, and therefore, the adding crank A67 or A68 will remain in its forward position until 40 such time as the pin D13 engages the forward side of the flying lever D53, for instance.

As thus far described, the mechanism is constructed and operates the same as set forth in my co-pending application, Serial No. 470,108, filed December 30, 1908, such description being necessary to a clear understanding of the present improvements which I will now set forth in detail.

50 *The non-add key.*—The key K69 is used when it is desired to print an item which is not a total and is not intended to be added into either of the accumulators. Pivoted at 13L is a latch L158 adapted to enter a notch n' in the stem of the non-add key K69 when the latter is depressed and having a pin z on its lower end. Pivoted at 13L is a locking lever or latch L58 which is adapted to engage studs 115D and 116D on the members D58 and D59 when the left-hand end of said lever is elevated. The pin z coöperates with the underside of the left-hand end of the lever L58, and consequently, when the latch L158 is snapped into the notch n' in the non-add key, on the depre-

sion of said key, by the spring s' , the pin z raises the lever L58 into the position shown in Fig. 4, thus effectually blocking any movement of the accumulator controller pieces D58 and D59. If the non-add key is in the 70 raised position shown in Fig. 3 and the locking or blocking lever L58 has not been raised by other means hereinafter set forth, said lever L58 is disengaged from the studs 115D and 116D and the members D58 and D59 are 75 free for conditioning for the performance of addition in either or both accumulators. This same result—the blocking of the pieces D58 and D59—is accomplished by the depression of the non-add key in my co-pending 80 application, but the construction here provided is different.

Prevention of addition when taking a total or sub-total.—In the machine of my co-pending application, when a total or sub-total is taken and both accumulators are conditioned for addition, the amount taken from one accumulator will be automatically added into the other accumulator unless the second accumulator is first conditioned to prevent addition by the release of the adding key controlling that accumulator, or, if addition is occurring in both accumulators, due to the position of the carriage, the latter will have to be spaced out of tabulating position. The present improvements entirely prevent adding into the upper accumulator the amount of the total taken from the lower accumulator, and vice versa, and entirely prevent fictitious results from 90 the cause mentioned. This effect is produced by the provision on the bars L66 and L65 of cams or humps x , x' and a pin y on the locking lever L58. Normally the pin y is free of the humps or cams x , x' and consequently, if the carriage is out of tabulating 95 position, the locking lever L58 will be disengaged from the studs 115D, 116D, as shown in Fig. 3. Should either of the sub-total keys K64, K67 be depressed, the bar 100 L65 would cause its cam or hump x' to engage the pin y and elevate the locking lever L58 into engagement with the studs 115D, 116D. This action results because 105 the latches 56L and L60 push back the bar 110 L65 to enable the ends of the latches to snap into the notches in the stems of keys K64, K67, according to which sub-total key is depressed, as both cannot be depressed at the same time. Immediately the handle 115 of the machine is operated, the sub-total 120 may be taken from the given accumulator, but as the engagement of the lever L58 with the studs 115D and 116D eventually blocks any movement of the pieces D58, D59, the 125 position, latched or unlatched, of the latches D60, D61, is immaterial as the blocking action afforded by lever L58 places both accumulators in the non-add condition and it is, therefore, impossible for the sub-total 130

130

to be put into the other accumulator by the movement of the actuators R50. In this connection it should be understood that if the accumulator is set for addition, it 5 will add regardless of whether the actuators R50 are limited in their travel by the stops K23 on the numeral key stems or, on the other hand, by the amount of rotation permitted in the other accumulator.

- 10 If one of the total keys K63 or K66 is depressed for the purpose of taking a total, one or the other of the latches L56 or L59 moves and pushes the sliding bar L66, which results in the hump or cam x engaging the pin y and elevating the left-hand end of the locking lever L58 into engagement with the studs 115D, 116D. The result obtained is the same as with the sub-total keys, as blocking the pieces D58, D59 by the lever L58 15 prevents the performance of addition in either accumulator, and consequently the transfer of the total taken from one accumulator into the other accumulator is rendered impossible.
- 20 When a total or sub-total key, previously depressed, has risen, the restoration of the bars L65, L66 to normal position results in the disengagement of the humps x , x' from the pin y and the release of the locking lever L58 from the pieces D58, D59. The accumulators will, therefore, at once be re-conditioned for addition in both of them.

*Printing numbers without addition when the carriage is in tabulating position.—*In

- 35 the machine of my co-pending application aforesaid, when the traveling platen carrying carriage is in a given tabulating position, the latches D60, D61 are automatically disengaged from the pieces D58, D59 so that 40 as long as the carriage remains in that position, the handle is unlocked and items may be added into both accumulators simultaneously. In taking a total or sub-total in that machine when the carriage is in that 45 position, a fictitious addition occurs in the other accumulator unless the carriage be first spaced out of tabulating position and the appropriate operating keys employed for the purpose desired. A two-point stop 50 similar to the stop C96, Figs. 5, and 7, may be employed for the purpose of addition when the carriage is in adding tabulating position. Such a stop would have its two points adapted to coöperate with the points 55 w on the two outside levers F61 which are pivoted at F25 and are engaged with the links D64 of the latches D60, D61 and I do not intend, by the present improvements, to omit this function of the 60 machine. Such a stop could be placed at any position on the rack C91 carried by the traveling carriage.

It is frequently desirable, however, to set the carriage in tabulating position for the 65 purpose of printing or listing a series of

numbers or items without adding them into the accumulators. It becomes necessary, therefore, for the accomplishment of this new result, to provide means whereby the machine may be placed in a non-add condition when the carriage is in a given tabulating position. To that end, I provide a stop C96 which, instead of having only two points, as previously, is provided with but one point t and a bumper block t' , as shown 75 in detail in Fig. 7, and to provide an intermediate lever F610, which is engaged with a vertically movable link D640 pivoted at L580 to the locking latch L58. For the engagement of lever F610 to place the machine in a non-add condition, the one-point stop C96 shown in Fig. 7, is placed at any desired point on the rack C91, corresponding to the position where it is desired to list or print, without adding, a series of 80 numbers. When the stop C96 is in that position, the point t engages the point w' of the center lever F610, which thereupon lifts the link D640 and lifts the left-hand end of the locking lever L58 so that it engages the studs 115D, 116D and effectually blocks any movement of the controller pieces D58, D59, so that addition cannot be performed when the carriage is in non-add position even though the accumulators may 85 happen to be set for addition by the adding keys. Immediately the carriage is spaced away from that position, the usual functions of the machine may be carried out.

The tabulating key K10 engages the lever 100 F67 pivoted at F29 and having an arm F58. A lever F50, pivoted at F11, is engaged with the arm F58 at 14F. The carriage abutment F73 which is adapted to be interposed in the path of the block t' on stop C96, is raised and lowered by the lever F50. The escapement mechanism is operated by the parts F70, F13, F51, F52.

As in the machine of my co-pending application aforesaid, the operating handle of 110 the machine, or the starting bar (if motor driven) is normally locked, but is unlocked by a shaft L1 carrying a piece 51L adapted to coöperate with the pins D27, D28 on the latches D60, D61, and there is provided an arm 50L having a pin 15L adapted to coöperate with the piece 51L. A spring 81L connects the pieces 50L and 51L. The pin s' on piece 50L is engaged by the bars L65, L66 and also by a projection y' on the lever L58. Consequently, the operation of any total or sub-total key, the non-add key, or placing the carriage in adding-tabulating, or non-add-tabulating position will release the normally locked handle, or, starting bar. 120

Having thus described my invention, what I claim as new and desire to secure by Letters Patent, is:—

1. In an adding machine, the combination with a plurality of accumulators adapt- 125

ed to be set for accumulation either in one of them, or in a plurality of them simultaneously, of actuators adapted to coöperate with one of said accumulators, or with 5 a plurality of them simultaneously, means for taking a total from either accumulator, and means under the control of the means for taking totals adapted to prevent addition in the accumulators when a total is 10 taken.

2. In an adding machine, the combination with a plurality of accumulators adapted to be set for accumulation either in one of them, or in a plurality of them simultaneously, of actuators adapted to coöperate with one of said accumulators, or with 15 a plurality of them simultaneously, means for taking a sub-total from either accumulator, and means under the control of the 20 means for taking sub-totals adapted to prevent addition in the accumulators when a sub-total is taken.

3. In an adding machine, the combination with a plurality of accumulators adapted to be set for accumulation either in one 25 of them, or in a plurality of them simultaneously, of actuators adapted to coöperate with one of said accumulators, or with a plurality of them simultaneously, means 30 for taking a total from either accumulator, means for taking a sub-total from either accumulator, and means common to, and under the control of, the means for taking totals and sub-totals adapted to prevent addition in the accumulators when either a 35 total or a sub-total is taken.

4. In an adding machine, the combination with a plurality of accumulators adapted to be set for accumulation either in one 40 of them, or in a plurality of them simultaneously, of actuators adapted to coöperate with one of said accumulators, or with a plurality of them simultaneously, total 45 keys for the respective accumulators, and means under the control of the respective total keys adapted to prevent addition in the accumulators when a total is taken.

5. In an adding machine, the combination with a plurality of accumulators adapted to 50 be set for accumulation either in one of them, or in a plurality of them simultaneously, of actuators adapted to coöperate with one of said accumulators, or with a plurality of them simultaneously, sub-total keys for the 55 respective accumulators, and means under the control of the respective sub-total keys adapted to prevent addition in the accumulators when a sub-total is taken.

6. In an adding machine, the combination with a plurality of accumulators, of actuators adapted to coöperate therewith, total 60 keys for the respective accumulators, adding keys for the respective accumulators, and means under the control of the respective total keys adapted to prevent addition in an 65

accumulator which has been set for addition by the operation of its adding key, when a total is taken from the other accumulator.

7. In an adding machine, the combination with a plurality of accumulators, of actuators adapted to coöperate therewith, sub-total keys for the respective accumulators, adding keys for the respective accumulators, and means under the control of the respective sub-total keys adapted to prevent addition in an accumulator which has been set for addition by the operation of its adding key, when a sub-total is taken from the other accumulator.

8. In an adding machine, the combination with a plurality of accumulators adapted to be set for accumulation either in one of them, or in a plurality of them simultaneously, of actuators adapted to coöperate with one of said accumulators, or with a plurality of them simultaneously, total keys for the respective accumulators, and means under the control of the respective total keys adapted to prevent addition in the accumulators when a total is taken and for re-conditioning for addition, after such total has 85 been taken, all accumulators which were previously set for addition.

9. In an adding machine, the combination with a plurality of accumulators adapted to be set for accumulation either in one of them, or in a plurality of them simultaneously, of actuators adapted to coöperate with one of said accumulators, or with a plurality of them simultaneously, sub-total keys for the 100 respective accumulators, and means under the control of the respective sub-total keys adapted to prevent addition in the accumulators when a sub-total is taken and for re-conditioning for addition, after such sub-total has been taken, all accumulators which were previously set for addition.

10. In a key-set adding machine, the combination with a stationary accumulator, of key-controlled actuators adapted to coöperate therewith, a traveling carriage movable in relation to the accumulator, and means controlled by the traveling carriage adapted for preventing addition in the accumulator when the carriage is in a predetermined position.

11. In a key-set adding machine, the combination with a plurality of stationary accumulators, of key-controlled actuators adapted to coöperate therewith, a traveling carriage movable in relation to the accumulators, and means for preventing addition in all of the accumulators when the carriage is in a predetermined position.

12. In a key-set adding machine, the combination with a stationary accumulator, of key-controlled actuators adapted to coöperate therewith, a traveling carriage movable in relation to the accumulator, means adapted to prevent addition in the accumulator, and 130

regulable means on the carriage adapted to coöperate with the aforesaid means when the carriage is in different positions to place the accumulator in a non-add condition.

5 13. In a key-set adding machine, the combination with a stationary accumulator, of key-controlled actuators adapted to coöperate therewith, a traveling carriage movable in relation to the accumulator, means adapted to prevent addition in the accumulator, and a stop settable to different positions on the carriage adapted to coöperate with the aforesaid means to place the accumulator in non-add condition when the carriage is in 10 different predetermined positions.

14. In a key-set adding machine, the combination with a plurality of stationary accumulators, of key-controlled actuators adapted to coöperate therewith, a traveling carriage movable in relation to the accumulators, means adapted to prevent addition in 20 all of said accumulators, and regulable means on the carriage adapted to coöperate with the aforesaid means to place the accumulators in a non-add condition when the carriage is in a predetermined position.

15. In an adding machine, the combination with an accumulator, of actuators adapted to coöperate therewith, a carriage, a non-add key, and means common to the carriage and non-add key adapted to place the accumulator in a non-add condition when the non-add key is operated or when the carriage is in a predetermined position.

35 16. In an adding machine, the combination with a plurality of accumulators, of actuators adapted to coöperate therewith, a carriage, a non-add key, and means common to both accumulators and to the non-add key and carriage adapted to place both of the accumulators in a non-add condition when the non-add key is operated or when the carriage is in a predetermined position.

17. In an adding machine, the combination with a plurality of accumulators, of actuators adapted to coöperate therewith, a carriage, a non-add key, total keys for the respective accumulators, and means common to both accumulators and to the non-add key, total key, and carriage adapted to place both of the accumulators in a non-add condition when either of the total keys, or the non-add key is operated, or when the carriage is in a predetermined position.

55 18. In an adding machine, the combination with a plurality of accumulators adapted to be set for accumulation either in one of them or in a plurality of them simultaneously, of actuators adapted to co-60 operate with one of said accumulators, or with a plurality of them simultaneously, independent controlling members for the respective accumulators, total keys for the respective accumulators, a locking lever adapted, when set, to lock the controlling

members, and a sliding bar under the control of said total keys which sets the locking lever when either total key is operated, thereby placing both accumulators in a non-add condition when a total is taken 70 from either accumulator.

19. In an adding machine, the combination with a plurality of accumulators adapted to be set for accumulation either in one of them or in a plurality of them 75 simultaneously, of actuators adapted to coöperate with one of said accumulators, or with a plurality of them simultaneously, independent controlling members for the respective accumulators, sub-total keys for the 80 respective accumulators, a locking lever adapted, when set, to lock the controlling members, and a sliding bar under the control of said sub-total keys which sets the locking lever when either sub-total key is 85 operated, thereby placing both accumulators in a non-add condition when a sub-total is taken from either accumulator.

20. In an adding machine, the combination with a plurality of accumulators 90 adapted to be set for accumulation either in one of them or in a plurality of them simultaneously, of actuators adapted to coöperate with one of said accumulators, or with a plurality of them simultaneously, independent controlling members for the respective accumulators, total keys for the respective accumulators, sub-total keys for the respective accumulators, a locking lever adapted; when set, to lock the controlling 130 members, and two sliding bars, respectively under the control of the total and sub-total keys which are respectively adapted to set the locking lever when either total or sub-total key is operated, thereby placing both 135 accumulators in non-add condition when a total or sub-total is taken from either accumulator.

21. In an adding machine, the combination with a plurality of accumulators 110 adapted to be set for accumulation either in one of them or in a plurality of them simultaneously, of actuators adapted to coöperate with one of said accumulators, or with a plurality of them simultaneously, independent controlling members for the respective accumulators, total keys for the respective accumulators, a locking lever adapted, when set, to lock the controlling 115 members, a non-add key having means 120 adapted to set said locking lever when said non-add key is operated, and a sliding bar under the control of the said total keys which sets the locking lever, independently of the position of the non-add key, when either total key is operated, whereby both accumulators are placed in non-add condition when either the non-add key or either total key is operated.

22. In an adding machine, the combina-

- tion with a plurality of accumulators adapted to be set for accumulation either in one of them or in a plurality of them simultaneously, of actuators adapted to co-operate with one of said accumulators, or with a plurality of them simultaneously, independent controlling members for the respective accumulators, a locking lever adapted, when set, to lock the controlling members, a carriage, and means for setting the locking lever from the carriage when the latter is in a predetermined position, thereby placing the accumulators in non-add condition.
- 15 23. In an adding machine, the combination with a plurality of accumulators, of actuators adapted to co-operate therewith, independent controlling members for the respective accumulators, a locking lever adapted, when set, to lock the controlling members, latches for the controlling mem-
- bers, and independent stops on the carriage one of which is adapted, when the carriage is in a given position to release the latches for addition and the other, when the carriage is in a predetermined position, to set the locking lever, thereby placing the accumulators in non-add condition.
- 20 24. In an adding machine, the combination with an accumulator, of actuators adapted to co-operate therewith, a traveling carriage, normally locked means for operating the said actuators, and means controlled by the traveling carriage adapted for preventing addition in the accumulators and for automatically unlocking said operating means when the carriage is in a predetermined position.

In testimony whereof, I hereunto affix my signature.

HALCOLM ELLIS.
